UNITED STATES PATENT OFFICE.

GEORGE H. GOODMAN AND JAMES B. HUNT, OF OTEGO, NEW YORK.

PUNCH.

SPECIFICATION forming part of Letters Patent No. 294,991, dated March 11, 1884.

Application filed June 14, 1883. (No model.)

To all whom it may concern:

Be it known that we, GEORGE H. GOODMAN and JAMES B. HUNT, citizens of the United States of America, residing at Otego, in the 5 county of Otsego and State of New York, have invented certain new and useful Improvements in Metal-Punches; and we do hereby declare the following to be a full, clear, and exact description of the invention, such as will 10 enable others skilled in the art to which it appertains to make and use the same, reference being had to the accompanying drawings, and to letters or figures of reference marked thereon, which form a part of this specification.

This invention relates to certain new and useful improvements in metal-punches, its object being to provide a punch which will perforate with the application of less power than 20 the ordinary punch with a flat base, and which will cut a hole having smooth sides; and to this end our invention consists in providing a punch with cutting-edges which are inclined with respect to the base of the punch and are 25 equidistant from each other, as will be hereinafter more fully set forth, and pointed out in the claim.

In the annexed drawings, which illustrate our invention, Figure 1 is a side view of a 30 punch constructed in accordance with our invention. Fig. 2 is a perspective view, and Fig. 3 is a plan view.

A represents the body of a punch, which is cylindrical in shape and of the size which it is 35 desired to punch or perforate the metal. The upper part of the punch, by which it is attached to the machine, is of ordinary construction. This punch is provided on its lower end or cutting-face with two or more inclined 40 faces, B, which are equidistant from each other, and are formed by cutting away the lower portion of the punch on a straight line from its edge toward its center, so that the outer end or lower portion of the inclines B will be 45 equidistant from each other.

We are aware that prior to our invention metal-punches have been made to produce a shear cut by giving a spiral direction to the cutting-edge of the punch, and we do not 50 claim such as our invention, as a punch constructed in this manner has certain objections,

among which may be mentioned that when the punch is forced through the metal it will be caused to lean to one side, and the pressure upon the end of the same is not regular 55 until the whole fall of the punch is embedded in the metal. This point of objection will be readily understood by those skilled in the art. When a punch is provided with two or more shearing-edges, this objection is removed, as 60 the pressure is not exerted at a single point, but is distributed equally over the face of the punch.

We are also aware that punches have been constructed having circular recesses cut in 65 their sides and a flat base; but we deem this flat base an objection, as the shearing-edges upon a punch thus constructed do not come into operation until the flat base is fully embedded in the metal. By means of our improvement 70 it will be seen that the pressure is distributed equally upon the periphery, and a shearing cut commences from different points as soon as the same is forced into the metal; also, shearing-faces are provided upon the bottom 75 of the punch as well as its sides, as the lower faces of the same, as well as the outer side faces, are inclined.

If desirable, this punch may be provided with two or more inclined edges up to four 80 in number, and in every circumstance these inclined faces or ends of these inclines will be equidistant from each other and on a line with each other at the center of the punch. The punch is also provided with a center-pin, as 85 is usual.

Having thus described our invention, what we claim as new, and desire to secure by Letters Patent, is—

The herein-described punch, provided at its 90 lower portion with cutting-faces inclined in opposite directions, said faces crossing the base of the punch at its center, substantially as shown, and for the purpose set forth.

In testimony whereof we affix our signatures 95 in presence of two witnesses.

GEORGE H. GOODMAN.
JAMES B. HUNT.
